UNITED STATES PATENT OFFICE.

CLIFTON A. GLASS, OF KANSAS CITY, MISSOURI.

FLOATING ROOF FOR OIL TANKS.

Application filed April 18, 1924. Serial No. 707,429.

This invention relates to oil tanks and particularly to a floating roof to prevent evaporation of the highly valuable volatile constituents of the petroleum.

5 Floating roofs or decks have been provided prior to my invention but my invention contemplates the provision of means for maintaining a high efficiency in an inexpensive construction and the invention consists 10 in certain novel parts and combinations of parts, all of which will be specifically referred to hereinafter, reference being had to the accompanying drawings, in which

15 Fig. 1 is a vertical, longitudinal, sectional view through a tank having a floating roof constructed in accordance with my invention.

Fig. 2 is a detail perspective view of one 20 of the floatable sealing members.

25 Fig. 3 is an enlarged, sectional view showing one of the sealing members at the point of connection of two overlapping plates constituting the wall of the tank, and

Fig. 4 is a view of a slightly modified 30 form of sealing means.

The tank is of usual construction having a bottom 1, a vertical wall 2, a roof 3, a gauge hole cover 4, a breather pipe 5 and a roof support 6. The roof 3, however, need 35 not be air-tight because the floating roof or deck constituting my invention will seal off atmosphere from the oil.

The floating deck or roof is shown as in 40 the form of a pan having a bottom 7 and an inturned, outwardly extending flange 8 to provide a substantially wedge-shaped space 9 between the flange 8 and the wall 2 of the tank.

Bridging the space between the periphery 45 of the pan (which is substantially co-extensive with the cross sectional area of the tank) is a sealing means. The sealing means consists of a ring preferably made of a plurality of tubular sections 10, having flattened ends 11 and 12 and adapted to be inflated through a valve 13. Air will be introduced into the sections 10 at low pressure and the sections are preferably weighted with gravel, shot or other similar material indicated at 50 14 (Fig. 2) so that the tubular sealing means will tend to wedge against the inwardly inclined flange 8 and the wall 2 of the tank.

The flattened ends 11 and 12 overlap similar ends on complementary segmental sections to form a continuous ring around the 55 pan and while the ring may be made of one

piece, I prefer to construct it in sections because the sections can be more easily handled, shipped and set up than can a continuous ring. Another advantage is that should the ring become damaged at any point, it will be only necessary to insert a new section to restore the ring to its original condition.

It will be apparent that the sealing of the outer edge of the pan-shaped roof will be insured so in order to prevent evaporation through the opening 15 in the center of the pan through which the vertical 6 extends, I provide a conical flange 16, packed by a ring 17 similar to the sealing ring at the outer edge of the pan and I may provide a swing pipe compartment 18 with an opening 19 therein, through which a flexible connection 20 extends, accessible from the exterior of 75 the tank and connected to the swing pipe 21.

I have also shown a thief hole 22, having a cover 23 hinged at 24 and provided with a flexible connection 25 accessible from the gauge hole cover 4 so that the thief hole can 80 be opened for gauging, sampling and the like.

In Fig. 3 I have shown a lap joint 26 where two plates 27 and 28 join. This is the usual construction of the vertical wall of 85 the tank, the illustration in Fig. 3 being designed to show how the sealing means 10 will conform to the lap joint to absolutely maintain the seal.

The bottom of the deck may be provided 90 with a depending flange 29 if desired and a similar flange 30 may be provided for the hole 15 to prevent any vapor within the gauge hole cover escaping through the space between the roof and the wall of the tank 95 or through the opening 15.

The roof is preferably constructed of metal but by providing it in the shape of a pan it will be obvious that liability of it becoming submerged will be eliminated.

Instead of employing inflatable sections 10 I may provide a plurality of tubes 31 with springs 32 therein, the springs having the same effect in holding the tubes distended that the air has.

Other slight modifications may occur from time to time without departing from the spirit of the invention so I reserve the right to make such changes in form, proportion and minor details of constructions as properly come within the scope of the appended claims.

What I claim and desire to secure by Letters-Patent is:

1. A floating roof for tanks, comprising a metal sheet having an upwardly and inwardly inclined peripheral flange to provide an inclined wedging face, a depending circumferential flange on the bottom of the sheet adjoining said inclined flange, a packing between the upwardly and inwardly disposed flange and the side of the tank, the packing consisting of hollow tubing having deformable walls, and a coil spring within said tubing for tensioning the same against the wall of the tank.
- 15 2. A floating roof for tanks, comprising a metal sheet having an upwardly and inwardly turned flange to provide a bevel-shaped edge, a depending circumferential flange on the bottom of the sheet, and a packing between the upwardly and inwardly disposed flange and the side of the tank, the packing consisting of hollow tubing, the walls of which are deformable and means within said hollow tubing to tension the same.
- 20 3. A floating roof for tanks, comprising a pan-shaped member having an upwardly and inwardly disposed circumferential flange, in combination with sealing means comprising a sectional yielding member resting upon the flange and urged toward the wall of the tank by the inclination of the outer face of the flange.
- 25 4. A floating roof for tanks, comprising a pan-shaped member having an upwardly and inwardly disposed circumferential flange, in combination with sealing means comprising a sectional yielding member resting upon the flange and urged toward the wall of the tank by the inclination of the outer face of the flange, the sections of the sealing means having overlapping ends.
- 30 5. A floating roof for tanks, comprising a metal sheet having an upwardly and inwardly turned flange to provide a bevel-shaped edge; a depending circumferential flange on the bottom of the sheet, and a packing between the upwardly and inwardly disposed flange and the side of the tank, the packing consisting of hollow tubing, the walls of which are deformable and a coil spring within said hollow tubing for tensioning the same against the wall of the tank.

In testimony whereof I affix my signature.

CLIFTON A. GLASS.
